SPEAKER HOUSING FOR DRIVE-IN THEATRE

Samuel M. Reed, 2121 Routt, Lakewood, Colo. 80215

Filed Apr. 17, 1974, Ser. No. 461,522

Term of patent 14 years

Int. Cl. D14—01

U.S. Cl. D26—14 G

FIG. 1

FIG. 2

FIG. 5

FIG. 3

FIG. 4

FIG. 1 is a perspective view of a speaker housing for drive-in theatre showing the design of my invention;

FIG. 2 is a front view in elevation;

FIG. 3 is a side elevational view, the opposite side being substantially identical thereto;

FIG. 4 is a rear view in elevation; and

FIG. 5 is a top plan view thereof.

I claim:

The ornamental design for a speaker housing for drive-in theatre, as shown and described.
